(57) CLAIM

The ornamental design for a scarf including a textual pattern, as shown and described.

DESCRIPTION

FIG. 1 is a front elevation view of a scarf including a textual pattern being worn by a user according to one embodiment. FIG. 2 is a front perspective view of the scarf including a textual pattern in an unfolded configuration.

FIG. 3 is a rear perspective view of the scarf including a textual pattern in an unfolded configuration.

FIG. 4 is a front perspective view of the scarf including a textual pattern in a semi-folded configuration suitable for being worn by a user.

FIG. 5 is a right side elevation view of the scarf including a textual pattern, the left side elevation view being a mirror image thereof.

FIG. 6 is a top elevation view of the scarf including a textual pattern; and,

FIG. 7 is a bottom elevation view of the scarf including a textual pattern.

The broken lines showing a partial human figure in FIG. 1 illustrates the environment in which the design is used, and forms no part of the claim.

1 Claim, 6 Drawing Sheets
